UNITED STATES PATENT OFFICE

EARL A. BESSOM, OF MARBLEHEAD, MASSACHUSETTS, ASSIGNOR TO UNITED SHOE MANUFACTURING CORPORATION, OF PATERSON, NEW JERSEY, A CORPORATION OF NEW JERSEY

HEEL-SEAT FITTING MACHINE

Application filed June 22, 1928. Serial No. 287,429.

This invention relates to machines for use in the manufacture of shoes and is illustrated herein as embodied in a heel-seat fitting machine.

- 5 In the manufacture of shoes to which wood heels are to be attached, the heel-seat portions of the soles of the shoes are prepared for the reception of the concave attaching surfaces of the heels by trimming off surplus stock around the periphery of the heel-seat portion of the sole of each shoe and forming a heel breast receiving abutment at the heel breast line of the sole. This operation is commonly called heel-seat fitting.
- 10 15 The heel breast receiving abutments formed in the soles of shoes to which Louis heels are to be attached are often provided by making a transverse cut in the sole of the shoe, inclined forwardly toward the attaching surface of the sole, thus producing a flap having a thin end and a thicker base and serving as an abutment beneath which the projecting portion of the breast of a Louis heel can be positioned, as disclosed and claimed in Letters Patent of the United States No. 1,527,963, granted February 24, 1925, on an application filed in the names of John L. Preo and Isabelle Henne. The heel-seat fitting operation, including the forming of such an abutment, 20 25 has been successfully performed by heel-seat fitting machines of the type disclosed in Letters Patent of the United States No. 1,697,251, granted January 1, 1929, on an application filed in the names of Preo and Henne, and by improved machines of the same general type disclosed in Letters Patent of the United States No. 1,661,391, granted March 6, 1928, on an application filed in the name of William C. Stewart.
- 30 35 40 It is an object of the present invention to adapt machines of the type referred to above to perform the heel-seat fitting operation upon the soles of shoes to which Cuban heels are to be attached, though the invention is not limited to embodiment in machines of that type.

The breasts of Cuban heels do not project forwardly and overhang in the fashion characteristic of Louis heels and the heel breast receiving abutment used with such heels com-

monly takes the form of a pair of shoulders, one at each end of the heel breast line, these shoulders having approximately vertical surfaces curved or inclined transversely in accordance with the transverse curvature of the heel breast and deviating from the vertical, assuming the shoe to be positioned normally, only sufficiently to bring them into alignment with the breast surface of the heel. These shoulders commonly extend the full thickness of the sole at the edges of the sole and diminish in height toward the median portion of the shoe, the abutment usually taking the form of two separated portions between which the sole of the shoe has not been cut.

The illustrated machine, which comprises a preferred embodiment of the invention, is equally applicable to the performance of the heel-seat fitting operation upon shoes to which other kinds of heels having straight breasts are to be attached. It may also be used for the performance of the heel-seat fitting operation upon shoes to which Louis heels are to be attached. Accordingly, in this specification and the accompanying claims the word "abutment", where used broadly and without qualification, is intended to designate the surface or surfaces against which the heel bears at its forward extremity, regardless of the form of the surface and regardless of whether the surface is continuous or is formed of two portions separated or spaced apart.

With the above-stated object in view and in accordance with a feature of the invention, the illustrated machine is provided with a rotary cutter movable transversely across the sole of a shoe presented to the machine from one edge of the sole to the other. In order to control the movement of the abutment forming cutter in a simple fashion and in a manner which will not interfere with the other parts of the machine, the illustrated machine is provided with a guide extending transversely across the sole of a shoe carried by a suitable support and along which the cutter is moved as it operates upon the sole. The illustrated machine, like the heel-seat fitting machines referred to above, is also provided with a cutter for trimming

the surplus stock from and beveling the peripheral portion of the heel-seat of the sole, this cutter being controlled as it moves peripherally of the heel-seat in the manner disclosed in an application for Letters Patent of the United States, Serial No. 170,881, filed February 25, 1927, in the name of Harry A. Ballard.

A further feature of the present invention 10 comprises novel means for controlling the path of movement of the abutment forming cutter of the machine in such a manner that it will be moved heightwise of the sole of a shoe as it is moved transversely thereof. 15 This permits the width of the median portion of the sole untouched by the cutter to be varied in accordance with the size of the heel to be attached to the shoe. For that purpose the illustrated machine is provided with a 20 cam arranged to control the movement of the cutter heightwise of the shoe, the illustrated cam being made up of a plurality of relatively movable sections by adjustment of which the heightwise movement of the cutter 25 may be changed, thus adapting the machine to form the heel breast receiving abutment with accuracy on shoes of different widths.

In accordance with another feature of the invention, the machine is also provided with 30 means illustrated as a cam for controlling the movement of the abutment forming cutter lengthwise of the shoe so that the abutment will be given a transverse inclination corresponding to the transverse curvature of a 35 heel breast. Thus in the illustrated machine the abutment forming cutter, as it enters the sole at one edge thereof, is moving in a path arranged at about 70 degrees to the median line of the shoe and inclined rearwardly toward the median line of the shoe. After the 40 cutter has moved heightwise out of contact with the sole at the median portion thereof, its direction of movement is changed so that it enters the sole of the shoe and approaches 45 the other edge of the sole at an angle of about 70 degrees to the median line, the two ends of the path being symmetrical with respect to the median line of the shoe.

In accordance with a further feature of 50 the invention, the machine is provided with means, illustrated as a cam, arranged to control the angular relation of the cutter to its path of movement and formed to cause the angular relation of the cutter to the median 55 line of the sole to be the same in quantity but opposite in direction when the cutter is operating upon the sole at opposite sides of its median line. Thus, in the illustrated machine, the abutment forming cutter is rotated about an axis which diverges rearwardly 60 from the median line upon one side as the cutter approaches the median line from one side of the shoe and upon the other side as the cutter recedes from the median line upon 65 the other side of the shoe.

In order that the heel breast receiving abutment may be properly positioned lengthwise of the shoe, and in accordance with a further feature of the invention, the guide of the illustrated machine along which the cutter utilized to form the heel breast receiving abutment for Cuban heel work travels in its movement transversely across the sole of the shoe is arranged for adjustment lengthwise of the shoe. The illustrated machine is provided with a heel measuring gage comprising a fixed heel-engaging member and a movable heel-engaging member between which the heel to be attached to the shoe, or a heel like that heel, may be positioned. Suitable connections are provided between the guide for the abutment forming cutter and the movable gage member so that when the latter is brought into measuring engagement with a heel the former will be located lengthwise of the shoe in such a position that the cutter, as it moves along the guide, will form the heel breast receiving abutment on the shoe at the position appropriate for the reception of the heel measured by the gage. The rear end of the shoe is positioned both longitudinally and transversely by novel gage mechanism which constitutes still another feature of the invention.

Another feature of the invention comprises a presser-foot or holddown member adjacent to and arranged to travel in front of the abutment forming cutter as the latter moves transversely across the sole of a shoe, the holddown member being effective to prevent displacement of the sole of the shoe by the cutter and thus being effective also to insure that the cutter cuts and does not tear the sole. As illustrated, this abutment is spring-pressed toward the sole so that it may yield to conform to the transverse curvature of the sole. Still another feature comprises a hold-down member arranged to cooperate with the trimming cutter which removes the surplus material from the peripheral portion of the heel-seat of the sole of the shoe. When operating upon shoes the heel-seat portions of the soles of which are not attached, for example Goodyear welt shoes, the sole attaching seam of which does not extend any substantial distance back of the heel breast line, there is a decided tendency for the heel-seat portion of the sole to be displaced by the trimming cutter. To obviate this the invention provides a holddown member arranged to ride up over the edge of the sole as the trimming cutter is brought into engagement with the sole and to move with the cutter peripherally of the heel-seat portion of the sole. In the illustrated machine this holddown takes the form of a conical member surrounding the trimming cutter and spring-pressed toward the sole of the shoe.

In accordance with a further feature of the invention the work support, which in the

illustrated machine is movable into and out of operative relation to the heel-seat fitting instrumentalities of the machine, is provided with means by which it may be locked in operative position against forward as well as downward displacement. The general organization of the work support and its operating means is of the character disclosed and claimed in the above-mentioned application for Letters Patent of the United States filed in the name of Harry A. Ballard and includes a cam yieldingly operated as the crease plates are moved into the rand crease of the shoe. In accordance with the feature of the invention now under discussion, pawl and ratchet mechanism is provided automatically to lock the cam and the work support in operative position, means being provided to release the pawl from the ratchet during the first part of the reverse or work releasing movement of the controller.

The invention is herein illustrated as embodied in a heel-seat fitting machine of the general type disclosed in the above-mentioned Preo and Henne Letters Patent No. 1,697,251, and in Letters Patent No. 1,661,391 referred to, but it should be understood that in various of its aspects the invention is not so limited. Obviously, various of the features of the invention are capable of embodiment in machines of other types.

With the above and other objects and features in view the invention will now be described with reference to the accompanying drawings and pointed out in the claims.

In the drawings,

Figs. 1 and 2 are perspective views of a heel-seat fitting machine embodying the present invention;

Fig. 3 is a front elevation of the same machine;

Fig. 4 is a median section of the machine;

Fig. 5 is an elevation, partly in section, of a portion of the transmission mechanism by means of which the cutters of the machine are driven;

Fig. 6 is a plan view of the machine;

Fig. 7 is a side elevation of the cutter which forms the heel breast receiving abutment, together with the carriage upon which the cutter is mounted and showing also in cross-section the guide upon which the cutter travels;

Fig. 8 is a plan view of the cutter carriage and guide of Fig. 7;

Fig. 9 is a diagrammatic perspective view of an adjustable cam shown also in Fig. 8;

Fig. 10 is a vertical section showing the abutment forming cutter, its mounting, and a portion of the gearing by which it is driven;

Fig. 11 is a sectional view on the line XI—XI of Fig. 10;

Fig. 12 is a sectional view on the line XII—XII of Fig. 8;

Fig. 13 is a plan view of a gage by which

the heel-seat portion of a shoe is positioned in the machine;

Fig. 14 is a side elevation of the abutment forming cutter, drawn on a larger scale than in Fig. 10;

Fig. 15 is a detail view of a portion of the crease plate operating mechanism; and

Fig. 16 is a plan view of the rear portion of a shoe the heel-seat of the sole of which has been fitted by the illustrated machine.

The illustrated heel-seat fitting machine is of the same general type as the machine disclosed in the above-mentioned Letters Patent of the United States No. 1,661,391, granted on an application filed in the name of William C. Stewart. Like that machine it is provided with a frame comprising leg castings 20, 22 at the top of which is supported a bed casting 24 recessed at the front at 26, as best shown in Fig. 1, to provide room for the shoe which is to be operated upon. The shoe to be operated on is carried by a support 28 comprising a last pin 29 mounted for limited transverse movement in the upper end of a hollow post 30 in which is telescoped a post 32 pivoted to the frame of the machine at 34, a spring housed within the hollow post 30 and bearing at its lower end against the post 32 urging the post 30 and the last pin 29 upwardly. A bed plate 40 recessed at the front to conform to the recess 26 of the bed casting 24 is secured to the latter and movably supports a pair of work engaging and supporting crease plates 42, thin edges of which are formed and arranged to enter the rand crease of a shoe mounted upon a last carried by the last pin 29 when the support 28 is moved rearwardly into operative position, as shown in Fig. 4.

The outer margins of the crease plates 42 are circular, as indicated in Fig. 1, the crease plates being arranged for arcuate adjustment in a circular seat formed in the bed plate 40. The rand crease entering edges of the crease plates 42 have an approximately horseshoe-shaped form, half of the horseshoe being formed by the edge of each of the crease plates. The point at which these two edges meet is substantially in alignment with the back seam of a shoe carried by the work support when the latter is in its operative position and it is about this point that the crease plates are adjustable.

The machine is also provided with a templet comprising a pair of plates 46, 46 (Fig. 2) in which are formed the two halves of a horseshoe-shaped slot 48 serving to guide a shaft 50 (Fig. 4) upon which is mounted a rotary cutter 52 movable, when the templet members 46, 46 are in operative position, about the peripheral portion of the heel seat of the sole of a shoe carried by the work support 28 and having its rand crease entered by the plates 42. As shown in Fig. 4, the templet members 46 are, during the opera-

70

- tion of the machine, positioned vertically above the crease plates 42 and are adjustable about the same axis with respect to which the crease plates are adjusted so that the spread of the slot 48 may be readily varied in accordance with the size of the shoe to be operated upon. To facilitate the presentation of a shoe to the machine and its removal therefrom, the templet members 46 are supported by a table 53 consisting of a pair of parallel plates, one above the other, mounted for forward and rearward sliding movement in ways formed at the top of the frame of the machine.
- 15 The cutter-shaft 50 is supported in perpendicular relation to the table 53 by means of a sleeve or bushing 54 (Fig. 4) passing through appropriate large openings in the plates of the table 53, and provided with a circular plate 55 positioned between the plates of the table 53 and having an enlarged hub 56. A collar 57 clamped to the shaft 50 above the sleeve 54 prevents downward displacement of the cutter-shaft 50.
- 20 25 A lever 58 at the right hand side of the machine (as viewed in Fig. 2) is secured to a rock shaft 59 extending through the frame of the machine and having fast to its inner end an arm 60 (Fig. 4) to which is connected a rearwardly extending link 61 connected to the table 53 by a pin and slot connection. A spring 62 connected at one end to the link 61 and at the other end to the table 53 causes the table 53 to move forwardly as the upper 30 35 end of the lever 58 is moved forwardly and provides a yielding connection so that the lever 58 may be moved a short distance after the front of the table 53 comes into engagement with a stop 63 (see Figs. 2 and 6) arranged to limit its forward movement. The rear end of a dog 64 (Fig. 2) carried by the lever 58 is arranged for engagement with a shoulder 65 secured to the frame of the machine to retain the table 53 in its forward 40 45 position.
- 45 The means for moving the crease plates into and out of engagement with the rand crease of a shoe carried by the work support 28, after the latter has been moved rearwardly from the position shown in Figs. 1 and 2 to the position shown in Fig. 4, and for correspondingly adjusting the templet members 46, is of the character disclosed in said application for Letters Patent of the 50 55 United States Serial No. 170,881, filed in the name of Harrie A. Ballard. Accordingly, the machine is provided with a hand lever 66 fulcrumed at 67 to the frame of the machine and provided with an upwardly extending portion 68 to the upper end of which is connected a rearwardly extending link 70. The rear end of the link 70 is bifurcated and straddles a transversely extending lever 72 (Figs. 4, 6 and 15) the left-hand end of which 60 65 is fulcrumed to the frame of the machine at 73. A spring 74 (Fig. 4) is anchored at one end to the top of the link 70 and at the other end to the lever 72. The median portion of the lever 72 is connected by a pair of links 76 with the crease plates 42. Thus, when the forward end of the lever 66 is moved downwardly, the lever 72 will be moved forwardly and the crease plates 42 will be moved about their axis in such a manner that the spread of the opening between their thin rand 75 crease entering edges will be narrowed and the crease plates will be brought into engagement with a shoe carried by the work support 28 in the position shown in Fig. 4. On the other hand, when the lever 66 is moved upwardly, the spread of the opening between the rand crease entering edges of the crease plates will be widened.
- 80 85 The machine is also provided with another transversely extending lever 80 (Fig. 6) approximately parallel to the lever 72 and connected at its forward end with the templet members 46 by a pair of links 82. A spring 84 tends to urge the right-hand end of the lever 80 forwardly, thus narrowing the 90 spread of the horseshoe-shaped slot 48. An arm 86 depending from the lever 80 is, however, normally engaged by a corresponding arm 81 (Fig. 15) extending upwardly from the lever 72 in front of the arm 86 so that the lever 80 follows the lever 72 as the latter is swung about its fulcrum and, accordingly, the spread of the horseshoe-shaped slot 48 corresponds to that of the rand crease entering edges of the crease plates 42 when the 100 parts in operative position. For purposes of adjustment in setting up the machine and to compensate for wear the depending arm 86 of the lever 80 is provided with a stop screw 88 (Fig. 6) arranged to contact with the 105 standing arm 81 of the lever 72 and thus permitting relative adjustment of the crease plates 42 and the templet members 46.
- 110 115 To move the trimming cutter 52 peripherally of the heel-seat portion of the sole of a shoe to be operated on, a forwardly extending hand lever 92 is fulcrumed at 90 to the table 53. The hand lever 92 (Figs. 1, 2, 3 and 6) has fulcrumed to its median portion, at 94, a transversely extending hand lever 96 the left-hand half of which is widened, taking the form of a plate 98 (Fig. 6) and bearing upon the top of the table 53. Secured to the plate 98 is a gear housing and guard 100. The sleeve or bushing 54, in which the shaft 50 rotates, extends upwardly through the plate 98, so that the cutter-shaft 50 may be moved peripherally of the heel-seat of the shoe to be operated on by moving the levers 92, 96, one of which is held in each hand of the operator.
- 120 125 The driving means for the cutter 52 includes a vertical shaft 106 (Figs. 4 and 6), the lower end of which is coupled to the shaft 50 (Fig. 4). The shaft 106 rotates in 130

bearings carried by the housing 100 and fast upon it is a spiral gear 108 driven by a similar gear upon the forward end of a shaft 110, the rear end of which telescopes with and is splined to the forward end of another shaft 112 also extending rearwardly and having fast upon it a spiral gear 114 (Fig. 5) meshing with a similar gear 116 carried at the upper end of a vertical shaft 118 rotating in bearings provided by a gear casing 120 carried at the upper right-hand corner of the rear of the machine. At its lower end the shaft 118 is connected by a universal joint 122 to another vertical shaft 124, which latter is connected by a universal joint 126 with a third vertical shaft 128 carrying a spiral gear 130 driven from a larger spiral gear 132 mounted upon a shaft 134 which is connected by suitable coupling 136 (Figs. 2 and 6) to the rotor shaft 138 (Fig. 2) of a motor 140 carried by the lower portion of the frame of the machine. Thus it will be seen that the connections between the motor 140, which is stationary, and the cutter shaft 50 are such that the latter may be driven at all times regardless of the position of the table 53 and regardless of the traversing movement of the shaft 50 peripherally of the heel-seat of a shoe presented to the machine.

22 Co-operating with the work support 28 and the crease plates 42 to position the shoe to be operated upon by the machine is a gage, shown in Figs. 3 and 4, and in detail in Fig. 13. This gage comprises a back gage member 152, the work engaging portion of which is inclined forwardly and upwardly (as best shown in Fig. 4) and engages the counter portion of the shoe substantially at the back seam and just below the flange of the counter. The back gage member 152 may be adjusted forwardly or rearwardly in a groove formed in the bed plate 40 by means of a screw 156 (Fig. 4) provided with a pair of collars one forward and the other to the rear of a lug 158 depending from the back gage 152. The screw 156 is threaded, as shown in Fig. 4, into a portion of the bed plate 40. A centering gage member 160, the details of which are also shown in Fig. 13, is carried by the bed plate 40 adjacent to the back gage 152.

23 The centering gage member 160 also has a body portion 162, mounted for forward and rearward free sliding movement in a groove carried by the bed plate 40, and is provided at its forward end with a pair of arms each provided with an inclined surface 164 arranged to engage the sides of the counter portion of a shoe presented to the machine. The surfaces 164 are arranged to converge lengthwise of the shoe positioned in the machine so that if a shoe carried by the work support 28 strikes one of the surfaces 164 before it strikes the other, the shoe will slide relatively to the surfaces 164 with which it

is in contact until it contacts with the other gage surface 164, after which further rearward movement of the work support 28 and the shoe will cause the gage member 160 to move bodily rearwardly. The surfaces 164 are also arranged to converge heightwise of the shoe positioned in the machine so as to assure their engaging the shoe only along portions thereof adjacent to the sole of the shoe. Thus, the centering gage member 160 is operative to center the heel-seat portion of the shoe in the machine while the back gage 152 positions the shoe lengthwise in the machine. A light spring 163, the rear end of which is secured to a pin 165 carried by the gage member 160 and the forward end of which is secured to a stationary part, tends to hold the centering gage 160 forward.

24 The work support 28 is moved into and out of operative position with the aid of the hand lever 66 to which it is connected. Rigidly connected with the lever 66 is a downwardly extending arm 170 (Figs. 1 and 4) the lower end of which carries a pin 172 positioned in an approximately horizontal slot 174 formed near the rear end of a link 176 the forward end of which is bifurcated and is provided with a pair of short slots 177 (one in each of the bifurcations) through which pass pins 178 connecting the link 176 with a pair of duplicate cam members 180. A pair of rolls 182 carried by the hollow post or sleeve 30 of the work support 28 are arranged for operative engagement with the cams 180 when the latter are rotated in a counterclockwise direction from the position shown in Fig. 1 to the position shown in Fig. 4. A spring 184 connected at one end to the arm 170 and at the other end to a yoke 186 pivotally connected at 178 to the cam members 180 forms a yielding connection between the arm 170 of the lever 66 and the cams 180 so that the latter will move yieldingly in a rearward direction as the forward end of the lever 66 is depressed. On the other hand, when the forward end of the lever 66 is raised, the pin 172 strikes the forward end of the slot 174 and the cams 180 are positively rocked in a forward direction. As best illustrated in Figs. 2 and 4, pawl and ratchet mechanism 190 is provided to hold the lever 66 in any position to which it may be moved.

25 When the work support is in inoperative position, as shown, for example, in Fig. 1, the work support 28 is inclined forwardly, the hollow post 30 being elevated by its spring. When the operator places a shoe upon the last pin 29, however, he depresses the shoe and swings the work support 28 rearwardly at the same time moving the forward end of the lever 66 downwardly and manipulating that lever so that the crease plates 42 are brought into engagement with the rand crease of the shoe. The pressure of the inturned heel-seat portion of the shoe

upper against the lower surfaces of the crease plates 42 is sufficient to maintain the work support 28 depressed until the cam members 180 are moved into engagement with the rolls 182. Further depression of the forward end of the lever 66 causes the cam members 180 to move the work support 28 upwardly, the force required for this being transmitted through the spring 184 and, accordingly, being limited to what can be transmitted by that spring. To retain the cam members 180, the work support 28 and the shoe in the position to which they have thus been moved, and to prevent the displacement of the shoe under the forces incident to the trimming operation, pawl and ratchet mechanism is provided for locking or latching the cam members 180 in adjusted position. This, as best shown in Fig. 4, comprises a pair of stationary ratchet segments 190 secured to the frame of the machine, one ratchet segment or the other being engaged by one of two groups of pawls 192 pivoted at 194 to the cams 180. A pair of upwardly extending fingers 196 are fulcrumed at 34 to the frame of the machine. The rear surfaces of the upper ends of the fingers 196 are positioned for engagement by the forward end of the link 176 while the forward surfaces of the same portions of the fingers 196 are engaged by a pair of dogs 198 (Fig. 4) pivoted at 194 to the cams 180 and having portions 200 positioned to engage the lower surfaces of the pawls 192. Spring-pressed plungers 202 tend to hold the pawls 192 in engagement with the ratchet segments 190.

It will be seen that when the forward end of the lever 66 is depressed and the lower end of the arm 170 is moved to the rear, the fingers 196 will in no way interfere with the depression of the pawls 192, but when the forward end of the lever 66 is moved upwardly, the first effect of the corresponding movement of the link 176 will be to lock the fingers 196 slightly in a clockwise direction, as viewed in Fig. 4, thus rocking the dogs 198 in the same direction and causing them to lift the pawls 192, thus releasing the ratchet 190 so that the cam members 180 are freed and can rock in a clockwise direction to permit the lowering of the support 28.

At the left-hand side of the frame of the machine is a carriage 210 (Fig. 3) mounted for forward and rearward adjustment in accordance with the length to which a heel-seat is to be trimmed. Mounted for transverse sliding movement in this carriage is a bar 212 at the right-hand end of which is a knife or cutter 214 arranged by transverse movement of the bar 212 to cut transversely across the sole of a shoe carried by the work support 28, thus forming in the sole a flap having a base of substantial thickness and tapering to a thin end, which flap may serve as an abutment for a Louis heel as disclosed

in the above-mentioned Letters Patent of the United States No. 1,527,963, granted on an application filed in the names of Preo and Hennic. At its left-hand end the bar 212 is connected, as shown in Figs. 1, 3 and 6, by a link 216 to a bell crank lever 218 fulcrumed at 220 to the frame of the machine and arranged to be rocked by a treadle rod 222 to cause the knife 214 to cut transversely across the sole and then to be returned to its inoperative position, as shown in Fig. 2.

To adapt the machine to form heel breast receiving abutments for the reception of Cuban heels, the mechanism is provided which will now be described. Secured to the carriage 210 is a guide 224 (Figs. 1, 2, 3, 7 and 8) in the form of a bar, rectangular in cross-section, and spaced from and extending transversely across the sole of a shoe carried by the work support 28 and the rand crease of which is engaged by the crease plates 42. Mounted upon the bar 224 is a carriage 226 arranged for sliding movement along the bar 224 and thus transversely across the sole of a shoe positioned in the machine. The carriage 226 is provided with a pair of rearwardly extending guideways positioned below the guide 224 and in which a slide 227 is mounted for forward and rearward movement to control the position of an abutment 228 forming cutter 242 lengthwise of a shoe carried by the work support 28. At its rear end the slide 227 is enlarged as shown at 228 (Figs. 7 and 10) to form a bearing for a sleeve 229 to the upper end of which is clamped a collar 230 which bears on the slide part 228 and thus restrains the sleeve 229 from downward movement. A cutter carrier 232 is provided with an upstanding bearing member 234 extending through the sleeve 229 and secured against downward movement beyond the position shown in Fig. 10 by a collar 236 secured to its upper end. A cutter shaft 240 is carried in bearings formed in the carrier 232, the shaft 240 being inclined upwardly and forwardly with respect to the sole of a shoe in the machine, as best shown in Fig. 7. At its lower rearward end the shaft 240 carries a rotary cutter 242 (Figs. 7, 10 and 14) having the general form of two cones placed base to base and provided with two series of inclined cutting edges 244, 246 lying substantially in the surfaces of the two cones. The cutting edges 246 are arranged, as the carriage 226 is moved along the guide 224, to cut heel breast receiving abutments in the sole of a shoe carried by the work support 28 while the edges 244 remove surplus material adjacent to and to the rear of the abutment thus formed, the relation of the cutter to the shoe as the cutter starts its operation being indicated diagrammatically in Fig. 7. This cutter is disclosed and claimed in my copending application Serial No. 377,438 filed July 12, 1933.

11, 1929, and the details of its construction are accordingly not claimed herein.

The driving mechanism for the cutter 242 includes a spur gear 250 (Fig. 10) fast upon the cutter shaft 240 meshing with a similar but larger gear 252 (Fig. 10) secured to a shaft 254 also carried by the cutter carrier 232. A spiral gear 256 is also fast upon the shaft 254 and meshes with a spiral gear 258 carried by a vertical shaft 260 having a bearing in the cutter carrier 232 and having upon its upper end a spiral gear 262 meshing with a spiral gear 264 carried by a horizontal shaft 268 (Fig. 8) extending rearwardly and connected by a universal joint 270 with a shaft 272 the rear end of which telescopes in and is splined to a horizontal shaft 274 (Fig. 4) connected by a universal joint 276 with a short shaft 278 on which is mounted a spiral gear 280 (Fig. 5) meshing with another spiral gear 282 fast upon the shaft 118 somewhat below the spiral gear 166. Thus it will be seen that the cutter 242 is driven continuously and at high speed from the motor 140 regardless of the position of the carriage 226 upon the guide 224. The upper end of the shaft 260 and the forward end of the shaft 268 both have a bearing in a housing 283 which contains the spiral gears 262, 264, this housing being provided with a boss 284 having a bearing in an arm 285 formed as an extension of the collar 236. Thus, the housing 283 can pivot about the shaft 260 relatively to the cutter carrier 232 as the carriage 226 and the parts carried thereby are moved along the guide 224.

As the cutter 242 is moved transversely across the sole of a shoe carried by the work support 28 from one edge of the sole to the other at its heel breast line, it is desired that the cutter 242 shall follow a path closely approximating the transverse curvature of the breast of a Cuban heel. It is for this purpose that the slide 227 is provided. The slide 227 carries a cam roll 292 (Fig. 8) positioned in a cam groove 294 formed in the lower surface of the guide 224 and of such a configuration that, as the carriage 226 is moved transversely of the shoe on the guide 224, the cutter carrier 232 and the cutter 242 will be moved longitudinally of the shoe in a path inclined to correspond to the curvature of the breast of a Cuban heel, that path being symmetrical with respect to the median line of the sole of a shoe carried by the work support and positioned by the gage members 152, 160. As illustrated, the path of the cutter 242 is inclined at about 70 degrees to the median line of the sole, as indicated by the position of the abutments 293 in the sole 295 of the shoe 297 shown in Fig. 16.

In order that the heel breast receiving abutments will extend through the full thickness of the sole at the edges of the sole and will gradually diminish in depth toward the

median line of the sole, terminating, however, before the median line is reached, means is provided for moving the cutter heightwise of the shoe as it moves transversely across the sole. For this purpose, the sleeve 229 is arranged for vertical movement with respect to the enlarged portion 228 of the slide 227 and the carriage 226. Fulcrumed at 300 (Fig. 7) to the carriage 226 are a pair of levers 302 having at their rearward extremities a pair of pins 304 to which are pivoted a pair of blocks 306 positioned in slots formed in the collar 230. One of the levers 302, the left-hand one as viewed in Fig. 8, is provided with a gear segment 308 (Fig. 7) meshing with a rack bar 310 mounted for forward and rearward sliding movement in the carriage 226. The rack bar 310 carries a roll 312 (Fig. 8) positioned in a cam groove 314 formed in the upper surface of the guide 224 and of such a formation that, as the carriage 226 and the cutter 242 move from the position shown in Fig. 8 toward the left, the cutter 242 enters the sole to its full depth. As the roll 312 reaches the position 316, however, the cutter 242 by that time having entered the sole, the rack bar 310 is moved rearwardly, rocking the left-hand lever 302 in a clockwise direction, as viewed in Fig. 7, and gradually lifting the cutter 242 so that the latter passes out of the sole at the point indicated at 315 in Fig. 16 before the median line of the sole is reached. After the cutter 242 passes the median line of the sole, the roll 312 reaches the position 318 (Fig. 8) in the cam groove 314 and the cutter 242 is lowered so that it enters the sole at the point indicated at 317 in Fig. 16, finally cutting through the entire thickness of the sole before the edge of the sole is reached. The relation of the cutter 242 to the sole 295 of the shoe, at the time the cutter enters the sole, is indicated diagrammatically in Fig. 7.

In order to permit the machine to operate effectively upon shoes of different widths and to permit the two separated portions of the heel breast receiving abutment to be spaced different distances apart, portions of the surfaces that form the cam groove 314 are formed upon a number of relatively adjustable parts, as best shown in Figs. 8 and 9. Thus, the forward surface of the cam groove 314 is formed upon two portions 320, 322 relatively adjustable by means of a screw 323 having right and left-hand threaded portions threaded into these parts and having a knurled head 324 positioned in a slot 326 formed in the guide bar 224 and preventing longitudinal movement of the screw.

A stationary member 328 secured to the guide bar 224 has a surface also forming a part of the cam groove 314 and overlapping the cam surfaces formed upon the parts 320, 322, regardless of the adjustment of those parts. A portion of the rear surface of the

cam groove 314 is also made up of surfaces formed on overlapping parts of the members 320, 322. Thus, the heightwise movement of the cutter 242 can be varied by manual adjustment of the screw 323 in accordance with the width of the shoe to be operated upon. As shown in Fig. 8, a scale 330 is provided on the guide 224 to facilitate this adjustment.

10 In order that the cutter 242 shall act efficiently and shall not tear the material of the sole, it is arranged to enter the sole in such a manner that the projection of its axis upon the plane of the tread surface of the sole will be inclined rearwardly from the median line of the sole, the inclination being the same in degrees but opposite in direction in operating upon opposite sides of the sole. To accomplish this, a cam groove 334 (Fig. 8) is formed in the lower surface of the guide 224. In this cam groove is positioned a roll 336 carried by a rod 338 (Figs. 7, 8 and 10) mounted for forward and rearward sliding movement with respect to the slide 227. Near its rearward end the rod 338 is provided with a series of rack teeth 339 engaging with elongated pinion teeth 340 formed on the bearing member 234. Thus, movement of the rack bar 338 relatively to the slide 227 will rotate the cutter carrier 232 about a vertical axis. The formation of the cam groove 334 is such that the cutter 242 enters the sole with the projection of its axis upon the plane of the tread surface of the sole at about nine degrees to the median line of the sole and diverging rearwardly therefrom. After the cutter has been moved heightwise out of engagement with the sole, the cam 334 moves the rack bar 338 to swing the cutter carrier 232 about eighteen degrees in a counterclockwise direction, as viewed in Fig. 8, this being accomplished by the portion of the cam 334 indicated at 341 in Fig. 8, so that the projection of the axis of the cutter 242 upon the plane of the tread surface of the sole is brought into a position at nine degrees to the median line of the sole and diverging rearwardly therefrom on the other side of the median line.

50 A pair of springs 346 (Fig. 7) secured at one end to the cutter carrier 232 and at the other end to the rearward portion 228 of the slide 227 tends to counterbalance the weight of the cutter carrier 232 and the parts carried thereby and facilitates the lifting thereof.

55 In order that the angular relation of the cutter shaft 240 to its path of movement may be maintained in the desired relation, notwithstanding the back-lash which is unavoidable, the cutter carrier 232 is provided with an outwardly extending arm 350 (Figs. 7, 10 and 11) provided with a pair of holes 352, 354 (Fig. 11) arranged alternatively to receive the rounded upper end of a pin 356

(Fig. 10) extending upwardly from a bracket 358 which depends from the slide 227. When the cutter carrier 232 is in the elevated position which it occupies while the cutter passes over the median portion of the sole of the shoe, the finger 350 is sufficiently elevated to clear the upper end of the pin 356, but as the cutter carrier 232 is moved downwardly under the control of the cam groove 314, one hole or the other, according to the angular position of the cutter carrier, will receive the pin 356 so that the cutter carrier will be held securely in position while the cutter 242 is operating upon the sole.

60 The cutter 242 should, when in its inoperative position, just clear the top of the crease plates 42. To facilitate its vertical adjustment, a slot is formed in the sleeve 229 in which is received the flat head of a screw 355 (Fig. 10) threaded into the collar 230. The upper end of the screw is slotted so that it may be engaged and turned by a screw driver. It will be seen that when the clamp screw which secures the collar 230 to the sleeve 229 is loosened, rotation of the screw 355 will adjust the collar 230 lengthwise of the sleeve 229, thus raising or lowering the cutter carrier 232. When the adjustment has been made, the clamp screw of the collar 230 is again tightened so that the adjustment will be maintained.

65 To prevent displacement of the sole by the cutter 242, particularly when operating upon shoes the heel-seat portions of the soles of which have not been attached, the machine is provided with a hold-down member 360 (shown in Fig. 7 but omitted from Fig. 4 to avoid confusion) secured to the cutter carrier and mounted to engage the uncut sole just ahead of the cutter 242 as the latter moves across the sole. The hold-down member 360 is mounted for swinging movement heightwise of the shoe about a horizontal pin 362 carried by a bracket 364 secured to the cutter carrier 232 and is pressed yieldingly downwardly by a spring plunger 366 also housed in the bracket 364.

70 Similarly, the rotary cutter 52 which trims surplus stock from the peripheral portion of the heel-seat is provided with a hold-down member 370 (see Fig. 4) in the form of a truncated cone surrounding the cutter 52 and spring-pressed downwardly by a spiral spring 372 surrounding the reduced upper end of the hold-down 370, the spring 372 bearing at its lower end against a shoulder formed on the hold-down 370 and at its upper end against a collar 374 clamped to an extension 375 of the bushing 54. A pin 377 passes through the hold-down 370 into a slot formed in the extension 375 and prevents excessive downward displacement of the hold-down 370. As the table 53 is brought forwardly into operative position, the conical surface of the hold-down member 370 rides

up over the sole 295 of the shoe 297 so that the plane end surface of the holddown member engages the tread surface of the sole as the cutter 52 is moved peripherally about the heel-seat to trim and bevel the heel-seat. Thus, the holddown 370 exerts a substantial yielding pressure upon the sole and is effective to prevent displacement of the sole by the cutter 52 even though the heel-seat portion of the sole is not secured to the shoe.

The carriage 210, which carries the cutter bar 212 and the guide 224 for the cutter 242, is forwardly and rearwardly adjustable, for which purpose it is provided with a boss 380 (Fig. 1) internally threaded to receive an external thread 382 (Figs. 1 and 6) formed on the projecting hub of a dial member 384. The hub 384 is internally threaded to receive a thread 386 formed upon the stem of a dial 388, the arrangement being of the character disclosed in Letters Patent of the United States No. 1,661,391, granted on an application filed in the name of William C. Stewart. A set-screw 389 is provided by which the dial 384 and screw 382 may be clamped in position when it is not desired to use them, as when using a heel measuring gage, which will presently be described.

When using the knife 214 to form abutments for Louis heels, the carriage 210 may be adjusted by setting the dials as described in said Letters Patent No. 1,661,391. When operating upon shoes to which Cuban heels are to be attached, however, a more accurate lengthwise adjustment of the carriage 210 than can be obtained by the dial mechanism is desirable. Accordingly, the carriage 210 is provided with a table 400 having toward its forward end a convex gage member 402 of a curvature corresponding to that of the breast of a Cuban heel. Carried by the frame of the machine and cooperating with the gage member 402 is a fixed gage member 404 arranged to engage the rear end of a heel positioned upon the table 400. Thus, a heel 406, either the heel which is to be attached to the shoe to be operated upon or a heel like that heel, may be placed upon the table 400 and moved by rotating the dial 388, thereby moving the carriage 210 until the heel is clamped lightly between the gage members 402, 404 and is measured thereby. As the guide 224 is also carried by the carriage 210, the position of the cutter 242 forwardly and rearwardly of the machine is thus controlled by the length of the heel 406 in the gage 402, 404. In order to limit the forward movement of the cutter 52 in accordance with the length of the heel 406 measured by the gage 402, 404, or, when Louis heel work is being done, in accordance with the setting of the dials 384, 388, a plate 410 (Figs. 1, 8 and 12) is adjustably secured to the guide bar 224 in such a position that it will not interfere with the movement of the carriage 226 and its as-

sociated parts. The rear edge of this plate 410 is long enough to extend across both ends of the horse-shoe-shaped path of movement of the hub 56 when operating upon all kinds of shoes. Thus, the length of the trimming 70 cut is coordinated with the position of the heel breast receiving abutment formed by the machine.

In order to move the carriage 226 transversely of the machine to cause the cutter 242 to form a heel breast receiving abutment in the sole of a shoe, the carriage 226 is connected by a link 420 (Fig. 2) to a rack bar 422 mounted for horizontal sliding movement in ways 424 carried by the frame of the machine 80 and provided with inclined teeth. A rack bar 426 mounted in ways 428 extending at right angles to the ways 424 is also provided with inclined teeth meshing with the teeth of the rack bar 422 in such a manner that downward movement of the rack bar 426 will cause the rack bar 422, the carriage 226 and the cutter 242 to move to the left and upward movement of the rack bar 426 will cause those parts to move to the right. The lower end of the rack bar 426 is connected by a link 428 to a hand lever 430 fulcrumed at 432 to the frame of the machine for vertical swinging movement.

The illustrated machine may be used to 95 perform the heel-seat fitting operation upon shoes to which Louis heels are to be attached in the manner described in the above-mentioned Letters Patent No. 1,661,391, the cutter 214 cutting a flap in the sole beneath which 100 the forwardly projecting portion of the breast of the heel is positioned. When using it to perform the heel-seat fitting operation upon a shoe to which a Cuban heel is to be attached, the operator places the heel to be attached to the shoe, or a heel like that heel, on the table 400, turning the dial 388 until the heel is clamped lightly between the gage members 402, 404. This sets the carriage 210, 105 guide bar 224 and the plate 410 in the appropriate positions for the shoe to be operated upon. He then places the last upon which the shoe is carried on the last pin 29, depressing the work support 28 and moving it rearwardly so that the rand crease of the shoe 110 may be engaged by the edges of the crease plates 42. He then depresses the lever 66, moving the edges of the crease plates 42 into the rand crease and causing counterclockwise movement of the cams 180 (as viewed in Fig. 4), thus causing the spring 184 to urge the work support yieldingly upwardly, and finally causing one of the pawls 192 to lock the work support in position so that it can not be forced forwardly or downwardly by the cutter 52. He then grasps the lever 58, moving the table 53 forwardly until it engages the stop 63. Next he grasps the hand levers 92 and 96, moving the cutter 52 peripherally of the heel-seat portion of the sole of the shoe 130

under the control of the guide slots 48 of the templet members 46 which have been positioned in accordance with the position of the crease plates 42 so that the spread of the slot 48 is appropriate to the particular shoe to be operated upon. This causes the cutter 52 to trim and bevel the periphery of the heel-seat of the sole as indicated at 434 in Fig. 16, the beveling cut ending at about the position indicated at 436 in dotted lines. The lever 58 is then moved rearwardly, withdrawing the table 53 and the cutter 52, and the lever 430 is moved downwardly, causing the carriage 226 to move to the left so that the cutter 242 enters the sole of the shoe at the right-hand side of the machine and moves transversely across the sole from one edge to the other in a path the operative portions of which are substantially straight but correspond closely in inclination to the transverse curvature of the breast of a Cuban heel. During this movement, as already set forth, the cutter 242 is moved heightwise of the shoe so that the heel-seat receiving abutment formed is in two parts separated by the uncut median portion of the sole. While the cutter is passing idly over this uncut median portion of the sole, its axis is swung from an angle of about nine degrees on one side of the median line of the sole to an angle of the same size on the other side of the median line, so that the cutter both enters and leaves the sole with its axis at an advantageous angle to its path of movement.

Having thus described my invention, what I claim as new and desire to secure by Letters Patent of the United States is:

1. A heel-seat fitting machine having a rotary cutter movable transversely across the sole of a shoe presented to the machine from one edge of the sole to the other substantially at its heel breast line to form a heel breast receiving abutment in the sole.

2. A heel-seat fitting machine having, in combination, a rotary cutter and means for presenting a shoe to the cutter, the cutter being constructed and arranged for movement transversely across the sole of the shoe from one edge of the sole to the other substantially at its heel breast line to form a heel breast receiving abutment in the sole.

3. A heel-seat fitting machine having, in combination, a support for a shoe, a rotary cutter, means for rotating said cutter continuously in one direction, and means for causing relative movement of the cutter and a shoe carried by the support in a direction transverse to the sole of the shoe to cause the cutter to operate on the sole of the shoe first at one end and then at the other end of its heel breast line to form a heel breast receiving abutment in the sole.

4. A heel-seat fitting machine having, in combination, a support for a shoe, a rotary cutter, means for rotating said cutter con-

tinuously in one direction, and hand-operated gearing arranged to cause relative movement of the cutter and the shoe carried by the support in a direction transverse to the sole of the shoe to cause the cutter to operate first at one end and then at the other end of the heel breast line of the sole of the shoe to form a heel breast receiving abutment in the sole.

5. A heel-seat fitting machine having, in combination, a support for a shoe, a pair of crease plates arranged to enter the rand crease of a shoe on the support, a rotary cutter, and means for moving the cutter transversely across the sole of the shoe from one edge of the sole to the other to cause the cutter to form a heel breast receiving abutment in the sole substantially at its heel breast line.

6. A heel-seat fitting machine having, in combination, a support for a shoe, and a rotary cutter movable transversely across the sole of a shoe carried by the support, from one edge of the sole to the other, to form a heel breast receiving abutment at the heel breast line of the sole, said cutter being rotated at high speed, at all times in the same direction, as it is moved across the sole to form a heel breast receiving abutment at the heel breast line of the sole.

7. A heel-seat fitting machine having, in combination, a support for a shoe, a rotary cutter continuously rotated in one direction, and means for moving the cutter transversely across the sole of a shoe carried by the support, from one edge of the sole to the other substantially at its heel breast line, to form a heel breast receiving abutment in the sole.

8. A heel-seat fitting machine having, in combination, a support for a shoe, means for trimming surplus material from the peripheral portion of the heel-seat of the sole of a shoe carried by the support, and a rotary cutter mounted for movement transversely across the sole of the shoe from one edge of the sole to the other along its heel breast line to form a heel breast receiving abutment in the sole.

9. A heel-seat fitting machine having, in combination, a support for a shoe, a rotary cutter mounted for movement transversely across the sole of a shoe substantially at the heel breast line thereof from one edge of the sole to the other, a stationary motor, and driving connections from the motor to the cutter arranged to permit movement of the rotating cutter across the sole of the shoe while rotating the cutter.

10. A heel-seat fitting machine having an electric motor, a rotary cutter, means for guiding the cutter in an approximately horse-shoe-shaped path to cause the cutter to trim surplus material from the peripheral portion of the heel-seat of the sole of a shoe, a second rotary cutter movable transversely across the sole of the shoe to form a heel breast receiving abutment in the sole of a shoe

substantially at its heel breast line, and driving connections from the motor to the two cutters operative to rotate the cutters continuously regardless of the positions to which they are moved.

11. A heel-seat fitting machine having, in combination, a support for a shoe, a cutter movable transversely across the sole of the shoe carried by the support to form a heel breast receiving abutment in the sole of the shoe substantially at its heel breast line, and a guide upon which the cutter is movable extending transversely across and spaced from the sole of the shoe carried by said support positively to support the cutter and constructed and arranged to control the position of the cutter lengthwise of the shoe as the cutter moves transversely of the shoe.

12. A heel-seat fitting machine having, in combination, a support for a shoe, a guide extending transversely across and spaced from the sole of a shoe carried by said support, and a rotary cutter movable along the guide transversely across the sole of a shoe carried by the support to form a heel breast receiving abutment in the sole substantially at its heel breast line.

13. A heel-seat fitting machine having, in combination, a support for a shoe, a guide positioned in the vicinity of the heel-breast line of the sole of the shoe carried by said support and extending transversely across and spaced from the sole of the shoe, a carriage carried by the guide, and a cutter carried by the carriage and movable therewith along the guide transversely across the sole of a shoe carried by the support to form a heel breast receiving abutment substantially at the heel breast line of the sole.

14. A heel-seat fitting machine having, in combination, a support for a shoe, a guide extending transversely of and spaced from the sole of a shoe carried by said support, a carriage carried by the guide, a cutter carried by the carriage and movable therewith along the guide transversely across the sole of a shoe on the support from one edge of the sole to the other to form a heel breast receiving abutment extending to both edges of the sole substantially at its heel breast line, and gearing operable to move the carriage along the guide.

15. A heel-seat fitting machine having, in combination, a support for a shoe, a guide extending transversely of the sole of a shoe carried by the support and spaced therefrom, a carriage carried by the guide, a rotary cutter movable with the carriage along the guide and transversely of the shoe, a motor, and driving connections from the motor to the cutter arranged to rotate the cutter as the cutter and carriage are moved along the guide transversely of the sole of the shoe.

16. A heel-seat fitting machine having, in combination, means to position a shoe to be

operated upon, a guide extending transversely across and spaced from the sole of a shoe positioned by said means, means for adjusting the guide lengthwise of the shoe, and a cutter movable along the guide transversely across the sole of the shoe in a path controlled by the guide to form a heel breast receiving abutment in the sole substantially at its heel breast line. 70

17. A heel-seat fitting machine having, in combination, a support for a shoe to be operated upon, a guide extending transversely across and spaced from the sole of a shoe carried by said support, means for adjusting the guide in a direction lengthwise of a shoe carried by the support, and a cutter movable on the guide and guided by the guide transversely across the sole of the shoe carried by the support to form a heel breast receiving abutment in the sole substantially at its heel breast line. 75

18. A heel-seat fitting machine having, in combination, a support for a shoe, a guide extending transversely across and spaced from the sole of a shoe carried by said support, said guide being mounted for adjustment in a direction lengthwise of a shoe carried by the support, a carriage movable along the guide transversely across the sole of the shoe, a cutter mounted on the carriage for movement therewith to form a heel breast receiving abutment in the sole substantially at its heel breast line, and gearing connected to the carriage and arranged to move the carriage along the guide transversely across the sole of a shoe carried by the support in any position of adjustment of the guide. 80

19. A heel-seat fitting machine having, in combination, a support for a shoe, a guide extending transversely across and spaced from the sole of a shoe carried by said support, said guide being mounted for adjustment in a direction lengthwise of a shoe carried by the support, a carriage movable along the guide transversely across the sole of the shoe, a rotary cutter mounted on the carriage for movement therewith to form a heel breast receiving abutment in the sole at its heel breast line, means for rotating said cutter continuously at high speed, and gearing connected to the carriage and operable to move the carriage along the guide transversely across the sole of a shoe carried by the support in any position of adjustment of the guide. 85

20. A heel-seat fitting machine having, in combination, a support for a shoe, a guide extending transversely across and spaced from the sole of a shoe carried by the support, a cutter movable along the guide transversely across the sole of a shoe carried by the support to form a heel breast receiving abutment in the sole substantially at its heel breast line, a pair of rack bars arranged substantially at right angles to each other and having inclined intermeshing teeth, a link 90

- connecting one of the rack bars with said carriage, and means for causing endwise movement of the other rack bar whereby the carriage is moved along the guide.
21. A heel-seat fitting machine having, in combination, a support for a shoe, a guide extending transversely across and spaced from the sole of a shoe carried by the support, a rotary cutter movable along the guide transversely across the sole of a shoe carried by the support to form a heel breast receiving abutment in the sole substantially at its heel breast line, a pair of rack bars arranged substantially at right angles to each other and having inclined intermeshing teeth, a link extending in the general direction of one of said rack bars and connecting said rack bar with said carriage, and a lever for causing endwise movement of the other rack bar whereby the carriage is moved along the guide.
22. A heel-seat fitting machine having, in combination, a support for a shoe, a rotary cutter mounted for movement transversely of the sole of a shoe carried by the support, and for rotation about an axis inclined upwardly relatively to the sole of the shoe and diverging from the sole toward the toe of the shoe, to form a heel breast receiving abutment at the heel breast line of the sole of the shoe.
23. A heel-seat fitting machine having, in combination, a support for a shoe, a rotary cutter mounted for rotation about an axis having a substantial upward inclination relatively to the sole of a shoe carried by the support and diverging from the sole toward the toe of the shoe, and means for causing relative movement of the shoe and the cutter in a direction transversely of the sole of the shoe to cause the cutter to form a heel breast receiving abutment in the sole of the shoe substantially at its heel breast line.
24. A heel-seat fitting machine having a support for a shoe, means for trimming surplus material from the peripheral portion of the heel-seat of the sole of a shoe carried by the support, a rotary cutter mounted for rotation about an axis inclined upwardly relatively to the sole of the shoe and diverging from the sole toward the toe of the shoe and for movement transversely of the sole of the shoe substantially at its heel breast line to form a heel breast receiving abutment in the sole.
25. A heel-seat fitting machine having a support for a shoe, a guide extending transversely of the sole of a shoe carried by the support and spaced therefrom, a carriage carried by the guide, and a rotary cutter carried by the carriage for rotation about an axis inclined upwardly relatively to the sole of the shoe and diverging from the sole toward the toe of the shoe.
26. A heel-seat fitting machine having, in combination, a support for a shoe, a guide extending transversely of the sole of a shoe carried by the support and spaced therefrom, a carriage carried by the guide, a rotary cutter movable with the carriage along the guide transversely of the shoe and mounted for rotation about an axis inclined upwardly relatively to the sole of the shoe and diverging forwardly from the shoe, a stationary motor, and driving connections from the motor to the cutter arranged to rotate the cutter while the cutter and carriage are moved along the guide transversely of the sole of the shoe.
27. A heel-seat fitting machine having, in combination, a support for a shoe, a rotary cutter mounted for rotation about an axis having a substantial inclination relatively to the sole of a shoe carried by the support and diverging from the sole toward the toe of the shoe, and manually operable means for causing relative movement of the shoe and the cutter in a direction transversely of the sole of the shoe to cause the cutter to form a heel breast receiving abutment in the sole of the shoe substantially at its heel breast line.
28. A heel-seat fitting machine having, in combination, a support for a shoe, a cutter movable transversely of the sole of a shoe carried by the support to form a heel breast receiving abutment in the sole, means to control the path of movement of the cutter lengthwise of the shoe as it moves transversely across the sole, and separate means to move the cutter about an axis substantially at right angles to the sole as it moves transversely of the sole.
29. A heel-seat fitting machine having, in combination, a support for a shoe, a cutter movable transversely of the sole of a shoe carried by the support to form a heel breast receiving abutment in the sole, a cam arranged to control the path of movement of the cutter lengthwise of the shoe as it moves transversely across the sole, and another cam arranged to move the cutter about an axis substantially at right angles to the sole as it moves transversely of the sole.
30. A heel-seat fitting machine having, in combination, a support for a shoe, a cutter movable transversely across the sole of a shoe carried by the support to form a heel breast receiving abutment in the sole, means for varying the position of the cutter lengthwise of the shoe as the cutter moves across the sole of the shoe, means for varying the position of the cutter heightwise of the shoe as the cutter moves across the sole of the shoe, and means for varying the angular relation of the cutter to its path of movement as it moves across the sole of the shoe.
31. A heel-seat fitting machine having, in combination, a support for a shoe, a cutter movable transversely across the sole of a shoe carried by the support to form a heel breast receiving abutment in the sole of the shoe, a cam arranged to vary the position of the cut-

ter lengthwise of the shoe as the cutter moves across the sole of the shoe, a second cam arranged to vary the position of the cutter heightwise of the shoe as the cutter moves across the sole of the shoe, and a third cam arranged to vary the angular relation of the cutter to its path of movement as it moves transversely across the sole of the shoe.

32. A heel-seat fitting machine having a work support, a rotary cutter movable transversely across the sole of a shoe carried by the support from one edge of the sole to the other in a curved path corresponding to the transverse curvature of a heel breast to form a heel breast receiving abutment in the sole, said cutter being arranged for rotation about an axis the projection of which on the plane of the tread surface of the sole of a shoe, as the cutter enters the sole at one side of the shoe, is inclined relatively to the median line of the sole, and means for shifting said axis of rotation while the cutter is at the median portion of the sole so that when the cutter approaches the other side of the shoe the projection of its axis on the plane of tread surface of the sole will be inclined in the opposite direction to the median line of the shoe.

33. A heel-seat fitting machine having a work support, a rotary cutter movable transversely across the sole of a shoe carried by the support from one edge of the sole to the other in a curved path corresponding to the transverse curvature of a heel breast to form a heel breast receiving abutment in the sole, said cutter being arranged for rotation about an axis the projection of which on the plane of the tread surface of the sole of the shoe, as the cutter enters the sole at one side of the shoe, is inclined relatively to the median line of the sole, and a cam arranged to shift said axis of rotation while the cutter is at the median portion of the sole so that when the cutter approaches the other side of the shoe the projection of its axis on the plane of the tread surface of the sole will be inclined in the opposite direction to the median line of the shoe.

34. A heel-seat fitting machine having a support for a shoe, a cutter movable transversely across the sole of a shoe carried by the support to form a heel breast receiving abutment in the sole of the shoe, a cam having two portions symmetrical with respect to an axis of symmetry and arranged to control the position of the cutter lengthwise of the shoe as the cutter moves transversely across the sole of the shoe, and a second cam arranged to control the angular relation of the cutter to its path of movement and formed to cause the angular relation of the cutter to the median line of the sole to be the same in degree but opposite in direction when the cutter is operating upon the sole at opposite sides of its median line.

35. A heel-seat fitting machine having, in combination, a support for a shoe, a rotary cutter arranged for movement transversely across the sole of a shoe carried by the support, from one edge of the sole to the other, to form a heel breast-receiving abutment in the sole of a shoe, and means for adjusting the cutter lengthwise of a shoe carried by the support so as to vary the position of the heel breast receiving abutment formed in the sole of a shoe.

36. A heel-seat fitting machine having, in combination, a support for a shoe, a rotary cutter, means for moving the cutter transversely of the sole of a shoe carried by the support at the heel breast line of the sole to form a heel breast receiving abutment in the sole, and means for moving the cutter heightwise of the shoe, as it moves transversely, to control the depth of the abutment.

37. A heel-seat fitting machine having, in combination, a support for a shoe, a guide extending transversely of the sole of a shoe carried by the support and spaced therefrom, a carriage movable along the guide transversely of the sole, a cutter carried by the carriage and movable therewith transversely of the sole to form a heel breast receiving abutment in the sole, and means for moving the cutter heightwise of the sole as it is moved transversely thereof to vary the depth to which the cutter penetrates the sole as it is moved transversely across the sole.

38. A heel-seat fitting machine having, in combination, a support for a shoe having a sole to be fitted for the reception of a heel, a cutter constructed and arranged for movement in the same general direction from one side of the sole to the other side of the sole to form a heel breast receiving abutment in the sole of the shoe, and means for varying the position of the cutter heightwise of the shoe as the cutter moves across the sole of the shoe, said means being adjustable to permit the heightwise movement of the cutter relatively to the shoe to be varied.

39. A heel-seat fitting machine having, in combination, a support for a shoe, a cutter movable transversely across the sole of a shoe carried by the support to form a heel breast receiving abutment in the sole of the shoe, and a cam arranged to vary the position of the cutter heightwise of the shoe as the cutter moves across the sole of the shoe, said cam being made up of a plurality of relatively adjustable parts constructed and arranged to permit the width of the effective portion of the cam to be varied while maintaining the shape of the lateral portions of said effective portion of the cam constant.

40. A heel-seat fitting machine having, in combination, a support for a shoe, a guide extending transversely of the sole of a shoe carried by the support and spaced therefrom, a carriage movable along the guide trans-

- versely of the sole, a rotary cutter carried by the carriage and movable therewith transversely of the sole to form a heel breast receiving abutment in the sole, and a cam for 5 moving the cutter heightwise of the sole as it is moved transversely thereof to control the depth to which the cutter penetrates the sole as it is moved transversely across the sole.
- 10 41. A heel-seat fitting machine having, in combination, a support for a shoe, a rotary cutter movable transversely across the sole of a shoe carried by the support to form a heel breast receiving abutment in the sole of the shoe, a cam for controlling the position of the cutter heightwise of the shoe arranged to cause the cutter to enter the sole at one edge through substantially the entire thickness of the sole, then, as the cutter is advanced across the sole, gradually to move heightwise of the sole, running out of the sole before the median line of the sole is reached, then, after the median line of the sole has been passed, to move heightwise of the sole in the opposite 15 direction, causing the cutter gradually to enter the sole and finally to cut through substantially the entire thickness of the sole shortly before it runs out at the edge of the sole, and means for rotating said cutter.
- 20 42. A heel-seat fitting machine having, in combination, a support for a shoe, a cutter movable transversely across the sole of a shoe carried by the support to form a heel breast receiving abutment in the sole of the shoe, a cam arranged to vary the position of the cutter heightwise of the shoe as the cutter moves across the sole of the shoe, and a cam arranged to vary the angular relation of the cutter to its path of movement as it moves 25 30 35 40 45 across the sole of the shoe, said first-named cam being made up of a plurality of relatively adjustable parts constructed and arranged to permit the width of the effective portion of the cam to be varied while maintaining the shape of the lateral portions of said effective portion of the cam constant.
43. A heel-seat fitting machine having, in combination, a support for a shoe, a rotary cutter movable transversely across the sole of a shoe carried by the support to form a heel breast receiving abutment in the sole of the shoe, and a cam for controlling the position of the cutter heightwise of the shoe arranged to cause the cutter to enter the sole at one edge through substantially the entire thickness of the sole, then, as the cutter is advanced across the sole, gradually to move heightwise of the sole, running out of the sole before the median line of the sole is reached, then, after the median line of the sole has been passed, to move heightwise of the sole in the opposite direction, causing the cutter gradually to enter the sole and finally to cut substantially through the entire thickness of the sole shortly before it runs out at the 50 55 60 65 70 75 80 85 90 95 100 105 110 115 120 125 130 other edge of the sole, said cam being made up of relatively movable parts so that the width of the median portion of the sole untouched by the cutter may be varied.
44. A heel-seat fitting machine having, in combination, a support for a shoe, a rotary cutter movable transversely across the sole of a shoe carried by the support to form a heel breast receiving abutment in the sole of the shoe, a cam for controlling the position of the cutter heightwise of the shoe arranged to cause the cutter to enter the sole at one edge through substantially the entire thickness of the sole, then, as the cutter is advanced across the sole, gradually to move heightwise of the sole, running out of the sole before the median line of the sole is reached, then, after the median line of the sole has been passed, to move heightwise of the sole in the opposite direction, causing the cutter gradually to enter the sole and finally to cut through substantially the entire thickness of the sole shortly before it runs out at the edge of the sole, said cam being made up of relatively movable parts so that the width of the median portion of the sole untouched by the cutter may be varied, and means for rotating the cutter.
45. A heel-seat fitting machine having, in combination, a support for a shoe, a cutter movable transversely across the sole of a shoe carried by the support to form a heel breast receiving abutment in the sole of the shoe, a cam arranged to vary the position of the cutter lengthwise of the shoe as the cutter moves across the sole of the shoe, a second cam arranged to vary the position of the cutter heightwise of the shoe as the cutter moves across the sole of the shoe, and a third cam arranged to vary the angular relation of the cutter to its path of movement as it moves transversely across the sole of the shoe, said second cam being made up of a plurality of relatively adjustable parts to permit the form of the cam and the heightwise movement of the cutter to be changed.
46. A heel-seat fitting machine having, in combination, a support for a shoe, a rotary cutter movable transversely across the sole of a shoe carried by the support from one edge of the sole to the other at its heel breast line to form a heel breast receiving abutment in the sole, a gage arranged to measure the heel which is to be attached to the shoe or a heel like that heel, and means for positioning the rotary cutter lengthwise of the shoe in accordance with the setting of the gage so that the heel breast receiving abutment formed in the shoe will be at the appropriate position to receive a heel of the size measured by the gage.
47. A heel-seat fitting machine having, in combination, a support for a shoe, a guide extending transversely across the sole of a shoe carried by the support, a cutter movable

along the guide from one edge of the sole to the other in a path controlled by the guide to form a heel breast receiving abutment in the sole, a gage arranged to measure the heel which is to be attached to the shoe or a heel like that heel, and means for positioning the guide lengthwise of the shoe in accordance with the setting of the gage so that the heel breast receiving abutment formed in the shoe 10 will be at the appropriate position to receive a heel of the size measured by the gage.

48. A heel-seat fitting machine having, in combination, a support for a shoe, a guide extending transversely across and spaced from the sole of a shoe carried by the support, a cutter movable on the guide transversely across the sole of a shoe carried by the support and guided by the guide to form a heel breast receiving abutment in the sole 15 at its heel breast line, a gage arranged to receive the heel which is to be attached to the shoe on the support or a heel like that heel and having a member movable to measure the length of the heel, and connections between 20 said movable gage member and said guide arranged to move the guide in a direction lengthwise of the shoe as the movable gage member is moved into position to measure the heel, whereby the cutter is positioned 25 lengthwise of the shoe to form a heel breast receiving abutment in the sole of the shoe at the position appropriate for the reception of the heel measured by the gage.

49. A heel-seat fitting machine having, in combination, means for positioning a shoe to be operated upon, a guide extending transversely across and spaced from the sole of a shoe positioned by said means, a rotary cutter movable along the guide transversely 30 across the sole of the shoe to form a heel breast receiving abutment in the sole, a gage arranged to receive the heel which is to be attached to the shoe or a heel like that heel and having a member movable to measure 35 the length of the heel, and connections between said movable gage member and said guide arranged to move the guide in a direction lengthwise of the shoe as the movable gage member is moved into position to measure 40 the heel, whereby the cutter is positioned lengthwise of the shoe to form a heel breast receiving abutment in the sole of the shoe at the position appropriate for the reception of the heel measured by the gage.

50. A heel-seat fitting machine having, in combination, a support for a shoe, a gage arranged to position the heel-seat portion of a shoe carried by the support longitudinally and transversely, a guide extending transversely across and spaced from the sole of a shoe carried by the support, a cutter movable along the guide transversely across the sole of the shoe in a curvilinear path controlled by the guide to form a heel breast receiving abutment in the sole at its heel breast

line, a gage arranged to measure the length of the heel which is to be attached to the shoe or a heel like that heel, and connections between said heel measuring gage and said guide arranged to position the guide lengthwise of the shoe in accordance with the length of the heel in the gage, whereby the path of movement of the cutter will be appropriate to form the heel breast receiving abutment in the sole of the shoe carried by the support.

51. A heel-seat fitting machine having, in combination, a support for a shoe, a plurality of crease plates arranged to enter the rand crease of a shoe carried by the support, 80 a gage arranged to position the heel-seat portion of the shoe longitudinally and transversely, a guide extending transversely across and spaced from the sole of a shoe carried by the support, a rotary cutter movable along the guide transversely across the sole of the shoe carried by the support to form a heel breast receiving abutment in the sole at its heel breast line, a gage arranged to measure the length of the heel which is to be attached to the shoe or a heel like that heel, and connections between said heel measuring gage and said guide arranged to position the guide in accordance with the length of the heel in the gage, whereby the path of movement of the cutter will be appropriate to form the heel breast receiving abutment in the sole of the shoe carried by the support.

52. A heel-seat fitting machine having, in combination, a support for a shoe, a cutter 100 movable transversely across the sole of a shoe carried by the support, from one edge of the sole to the other, substantially at its heel breast line, arranged to form a heel breast receiving abutment which is substantially vertical to the plane of the sole, and a hold-down member arranged to move with the cutter and to engage the sole in front of the cutter as the cutter moves transversely across the sole.

53. A heel-seat fitting machine having, in combination, a support for a shoe, a rotary cutter movable transversely across the sole of a shoe carried by the support from one edge of the sole to the other substantially at the heel breast line of the sole to form a heel breast receiving abutment therein, means for rotating the cutter, and a hold-down member arranged to move with the cutter and to engage the sole in front of the cutter as the cutter moves transversely across the sole.

54. A heel-seat fitting machine having, in combination, a support for a shoe, a guide extending transversely across the sole of a shoe carried by the support, a cutter carried by the guide and mounted for movement from one edge of the sole to the other, at its heel breast line, constructed and arranged to form a heel breast receiving abutment therein, a hold-down member mounted for

movement heightwise of the shoe in front of the cutter and arranged to press the sole by sliding engagement therewith in front of the cutter as the cutter moves transversely across the sole.

55. A heel-seat fitting machine having, in combination, a support for a shoe, a rotary cutter movable transversely across the sole of a shoe carried by the support substantially at the heel breast line thereof to form a heel breast receiving abutment in the sole, a holddown member mounted adjacent to the cutter for engagement with the sole in front of the cutter as the cutter is moved

10 transversely across the sole, and means for pressing the holddown member yieldingly against the sole.

56. A heel-seat fitting machine having, in combination, a support for a shoe, a guide

20 extending transversely across the sole of a shoe carried by the support, a cutter carried by the guide and mounted for movement from one edge of the sole to the other at the heel breast line of the sole constructed and

25 arranged to form a heel breast receiving abutment therein, a holddown member arranged to move with the cutter and to press the sole by sliding contact therewith in front of the cutter as the cutter moves transversely

30 across the sole, and means for pressing the holddown member yieldingly against the sole during the abutment forming movement of the cutter.

57. A heel-seat fitting machine having, in combination, a support for a shoe, a guide

35 extending transversely across the sole of a shoe carried by the support, a cutter carried by and movable transversely along the guide across the sole of a shoe carried by the sup-

30 port from one edge of the sole to the other at the heel breast line of the sole to form a heel breast receiving abutment therein, and a holddown member arranged to move with the cutter and to engage the sole in front of

45 the cutter as the cutter moves transversely across the sole.

58. A heel-seat fitting machine having, in combination, a support for a shoe, a pair of crease plates arranged to enter the rand

50 crease of a shoe carried by the support, a rotary cutter, means for guiding the cutter in an approximately horseshoe-shaped path peripherally of the heel-seat of the sole of a shoe carried by the support to trim surplus

55 material from the peripheral portion of the heel-seat of the sole, and a holddown member arranged to move with the cutter peripherally of the heel-seat of the sole in advance of the cutter to prevent displacement of the

60 sole.

59. A heel-seat fitting machine having, in combination, a rotary cutter, means for guiding the cutter in an approximately horseshoe-shaped path to trim surplus material from

65 the peripheral portion of the heel-seat of the

sole of a shoe, a holddown member adjacent to the cutter, and a spring arranged to press said holddown member toward the shoe to be operated upon, said holddown member being formed and arranged to engage and ride 70 over the margin of the sole of a shoe as the cutter is brought into trimming relation to the sole and to press the sole against the adjacent parts of the shoe so that the cutter can operate effectively upon a shoe the heel-seat portion of the sole of which is unattached 75 without danger of displacing the sole relatively to the remainder of the shoe.

60. A heel-seat fitting machine having, in combination, a rotary cutter, means for guid- 80

ing the cutter in an approximately horseshoe-shaped path to trim surplus material from the peripheral portion of the heel-seat of the sole of a shoe, and a conical holddown mem- 85

ber surrounding the cutter and from the small end of which the cutter projects, said holddown member being spring-pressed to- 90

ward the shoe to be operated upon and ar- 95

ranged to engage and ride over the margin 95

of the sole of the shoe as the cutter is brought 100

into trimming relation to the sole and there- 105

after to press the sole against the adjacent 110

parts of the shoe so that the cutter can oper- 115

ate effectively upon a shoe the heel-seat por- 120

tion of the sole of which is unattached with- 125

out danger of displacing the sole relatively to 130

the remainder of the shoe.

61. A heel-seat fitting machine having, in combination, a support for a shoe, a cutter

100 mounted for movement in an approximately horseshoe-shaped path peripherally of the heel-seat of the sole of a shoe carried by the support to trim surplus material therefrom, a holddown member adjacent to the cutter

105 and arranged to engage the heel-seat portion of the sole and to move with the cutter, a cutter arranged for movement transversely

110 across the sole of the shoe at its heel breast line, from one edge of the sole to the other, to form a heel breast receiving abutment in

115 the sole, and a holddown member adjacent to the abutment forming cutter arranged for engagement with the sole and for movement in advance of that cutter transversely across the sole.

62. A heel-seat fitting machine having, in combination, a support for a shoe, crease

120 plates arranged to enter the rand crease of a shoe carried by the support, said support

being mounted for movement heightwise of a shoe carried thereby into and out of oper- 125

ative relation to the crease plates, a cam ar- 130

ranged to move the work support into oper- 135

ative relation to the crease plates, and means

for locking the cam in position to hold the 140

work support in operative relation to the 145

crease plates.

63. A heel-seat fitting machine having, in combination, a support for a shoe, crease

140 plates arranged to enter the rand crease of a

- shoe carried by the work support, said work support being mounted for movement heightwise of a shoe carried thereby into and out of operative relation to the crease plates, a 5 cam arranged by rocking movement to move the work support into operative relation to the crease plates, means for locking the cam in position to hold the work support in operative relation to the crease plates, and 10 means for trimming surplus material from the peripheral portion of a shoe carried by the work support.
64. A heel-seat fitting machine having, in combination, a support for a shoe, crease plates arranged to enter the rand crease of a shoe carried by the work support, said work support being mounted for movement heightwise of a shoe carried thereby into and out of operative relation to the crease plates, a 15 cam arranged to move the work support into operative relation to the crease plates, means connected to the crease plates and to the cam and arranged to move the crease plates into the rand crease of a shoe on the support and to move the support heightwise of the shoe into operative relation to the crease plates, and pawl and ratchet mechanism arranged to lock the cam in position to hold the support in operative relation to the crease plates.
65. A heel-seat fitting machine having, in combination, a support for a shoe, crease plates arranged to enter the rand crease of a shoe carried by the support, said support being mounted for movement heightwise of a shoe carried thereby into and out of operative relation to the crease plates, a cam arranged to move the support into operative relation to the crease plates, means connected to the crease plates and to the cam and including a yielding connection whereby the crease plates may be moved into the rand crease of a shoe on the support and the support may be moved heightwise into operative relation to the crease plates and held there regardless of further movement of the crease plates into the rand crease of the shoe, and pawl and ratchet mechanism arranged to lock the cam in position to hold the work support in operative relation to the crease plates.
66. A heel-seat fitting machine having, in combination, a pair of crease plates arranged to enter the rand crease of a shoe, a support arranged to carry a shoe the rand crease of which is in engagement with said plates, said support being mounted for movement into and out of operative relation to the crease plates, a lever to move the crease plates into and out of the rand crease of a shoe carried by the support, a cam arranged to raise and lower the support, connections from said lever to the cam arranged to cause the cam to raise the support as the crease plates are moved into the rand crease of a shoe on the support and finally to position the work sup-
- port in accordance with the size of the shoe the rand crease of which has been entered by the crease plates, pawl and ratchet mechanism arranged to hold the support in operative position, and connections from said mechanism to the lever arranged to cause movement of the lever in a direction to withdraw the crease plates, also to withdraw the pawl from the ratchet and thereby to permit the cam to move in a direction to permit the lowering of the support as the crease plates are withdrawn.
67. A heel-seat fitting machine having, in combination, a pair of crease plates arranged to enter the rand crease of a shoe to be operated upon, a support arranged to carry a shoe the rand crease of which is in engagement with said plates, said work support being mounted for swinging movement into and out of operative relation to the crease plates about a transverse axis, a lever arranged by rocking movement to move the crease plates into and out of the rand crease of a shoe carried by the support, a cam engaging a roll carried by the work support and arranged by rocking movement to raise and lower the work support, connections from said lever to the cam arranged to cause the cam to raise the work support as the crease plates are moved into the rand crease of a shoe on the support and finally to position the support heightwise in accordance with the size of the shoe the rand crease of which is engaged by the crease plates, pawl and ratchet mechanism arranged to hold the work support in the position to which it is raised, and connections from the pawl to said lever arranged to cause movement of the lever in a direction to withdraw the crease plates, also to withdraw the pawl from the ratchet and thereby to permit the cam to move in a direction to permit the lowering of the work support as the crease plates are withdrawn.
68. A heel-seat fitting machine having, in combination, means for trimming surplus material from the peripheral portion of the heel-seat of the sole of a shoe, and means arranged to position a shoe in the machine relatively to said trimming means comprising a stationary back gage positioned to engage the shoe substantially at the back seam thereof and a gage member mounted for movement lengthwise of the shoe and spring-held forwardly, said gage member having a pair of surfaces arranged to engage the counter portion of the shoe and converging lengthwise of the shoe at such an angle that the shoe, upon being moved rearwardly into engagement with one of said inclined surfaces, will slide relatively thereto into engagement with the other inclined surface before the gage member will move rearwardly, whereby the heel-seat portion of the shoe is centered by said inclined surfaces and is positioned longitudinally by said back gage, said surfaces also

being arranged in converging relation to each other heightwise of the shoe to assure their engaging the shoe only along a portion thereof adjacent to the sole of the shoe.

- 5 59. A heel-seat fitting machine having, in combination, a cutter for forming a heel breast receiving abutment at the heel breast line of the sole of a shoe, means arranged to position a shoe in the machine relatively to 10 said cutter comprising a stationary back gage positioned to engage the shoe substantially at the back seam thereof and a gage member mounted for movement lengthwise of the shoe and spring-held forwardly, said member 15 having a pair of surfaces arranged to engage the counter portion of the shoe and converging lengthwise of the shoe at such an angle that the shoe, upon being moved rearwardly into engagement with one of said surfaces, 20 will slide relatively thereto into engagement with the other inclined surface before the gage member will move rearwardly, whereby the heel-seat portion of the shoe is centered by said inclined surfaces and is positioned 25 longitudinally by said back gage, said surfaces also being arranged in converging relation to each other heightwise of the shoe to assure their engaging the shoe only along a portion thereof adjacent to the sole of the 30 shoe.

- 30 70. A heel-seat fitting machine having, in combination, a support for a shoe having a sole to be fitted for reception of a heel, a guide extending transversely across and spaced from the sole of the shoe carried by said support, and a cutter movable along the guide transversely across the sole of the shoe upon the support in a curvilinear path controlled by the guide and constructed and arranged to form a heel-breast receiving abutment upon the sole of the shoe substantially at its heel-breast line as it moves from one side of the sole to the other side of the sole.

- 45 71. A heel-seat fitting machine having, in combination, a support for a shoe, a guide extending transversely across and spaced from the sole of the shoe carried by said support, and a cutter movable on the guide transversely across the sole of the shoe carried by the support in a path controlled by the guide and constructed and arranged to form a heel-breast receiving abutment upon the sole of the shoe as the cutter moves continuously from one side of the sole to the other side of the sole.

- 50 72. A heel-seat fitting machine having, in combination, a support for a shoe, a guide extending transversely across and spaced from the sole of the shoe carried by said support, and a cutter movable along the guide transversely of the sole of the shoe carried by the support constructed and arranged successively to form separate heel-breast receiving abutment portions upon the sole of the shoe at opposite sides of a heel-seat portion of the sole 60 as the cutter moves continuously from one

side of the sole to the opposite side of the sole.

73. A heel-seat fitting machine having, in combination, a support for a shoe, a cutter movable transversely across the sole of the shoe carried by the support from one side of the sole to the other substantially at its breast line, means for moving the cutter to form a substantially vertical heel-breast receiving abutment of varying height widthwise of the heel upon the sole of the shoe, and a hold-down member arranged to move with the cutter and to engage the sole in front of the cutter as the cutter moves transversely across the sole.

74. A heel-seat fitting machine having, in combination, a support for a shoe, a guide extending transversely across the sole of the shoe and carried by the support, a cutter carried by and movable along the guide from one edge of the sole to the other to form a heel-breast-receiving abutment in the sole, a gage arranged to measure the heel which is to be attached to the shoe or a heel like that heel, and means for positioning the guide lengthwise of the shoe in accordance with the setting of the gage so that the heel-breast-receiving abutment formed in the shoe will be in the approximate position to receive a heel of the size measured by the gage.

75. A heel-seat fitting machine having, in combination, a support for a shoe having a sole to be fitted for the reception of a heel, a cutter for trimming the marginal portion of the heel-seat-portion of the sole of the shoe upon the support, a guide extending transversely across and spaced from the sole of the shoe, means for adjusting the guide lengthwise of the shoe, and a cutter constructed and arranged to form a heel-breast-receiving abutment in the sole of the shoe and mounted for movement transversely of the sole from one side of the sole to the other in a path determined by the guide.

76. A heel-seat fitting machine having, in combination, a support for a shoe having a sole to be fitted for reception of a heel, a guide extending transversely across and spaced from the sole of the shoe carried by said support, and a cutter carried by and movable along the guide transversely across the sole of the shoe upon the support and constructed and arranged to form a heel-breast-receiving abutment upon the sole of the shoe substantially at its heel-breast line as it moves from one side of the sole to the other side of the sole.

77. A heel-seat fitting machine having, in combination, a support for a shoe having a sole to be fitted for the reception of a heel, a guide extending transversely across and spaced from the sole of a shoe carried by said support, and a cutter movable along the guide transversely across the sole of the shoe upon the support and constructed and arranged to form a heel-breast-receiving abutment on the

sole of the shoe substantially at the heel-breast line of the sole as it moves from one side of the sole to the other, said guide being constructed and arranged to change the direction of movement of the cutter transversely of the sole as the cutter moves from one side of the sole to the other.

78. A heel-seat fitting machine having, in combination, a support for a shoe having a sole to be fitted for the reception of a heel, a guide extending transversely across and spaced from the sole of a shoe carried by said support, and a cutter movable along the guide transversely across the sole of the shoe upon the support and constructed and arranged to form a heel-breast-receiving abutment on the sole of the shoe substantially at the heel-breast line of the sole as it moves from one side of the sole to the other, said guide being constructed and arranged to change the position of the cutter lengthwise of the shoe as it moves transversely of the shoe.

In testimony whereof I have signed my name to this specification.

EARL A. BESSOM.
